(57) **CLAIM**

I claim the ornamental design for an autonomous mobile robot, as shown and described.

DESCRIPTION

FIG. 1 is a front perspective view of an autonomous mobile robot, showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and

FIG. 9 is an enlarged front elevational view of the 9-9 portion of FIG. 3;

FIG. 10 is an enlarged rear elevational view of the 10-10 portion of FIG. 4;

FIG. 11 is an enlarged right side elevational view of the 11-11 portion of FIG. 7;

FIG. 12 is an enlarged left side elevational view of the 12-12 portion of FIG. 8;

FIG. 13 is a cross-sectional view taken along line 13-13 of FIG. 9 in which internal mechanisms are omitted; and,

FIG. 14 is a cross-sectional view taken along line 14-14 of FIG. 9 in which internal mechanisms are omitted.

The dashed broken lines show portions of the autonomous mobile robot that form no part of the claimed design.
